UNITED STATES PATENT OFFICE.

EDWARD HOPKINSON AND ALAN E. L. CHORLTON, OF SALFORD, ENGLAND.

ROTARY PUMP OR TURBINE.

SPECIFICATION forming part of Letters Patent No. 785,039, dated March 14, 1905.

Application filed August 2, 1904. Serial No. 219,253.

To all whom it may concern:

Be it known that we, EDWARD HOPKINSON and ALAN ERNEST LEOFRIK CHORLTON, subjects of the King of Great Britain and Ireland, residing at Salford Ironworks, Cross street, Salford, in the county of Lancaster, England, have invented a certain new and useful Rotary Pump or Turbine, (for which we have filed application for British Patent No. 8,855, dated April 18, A. D. 1904;) and we do hereby declare the following to be a full, clear, and exact description of the invention, such as will enable others skilled in the art to which it appertains to make and use the same.

This invention relates to improvements in rotary pumps or turbines of the type described in Reynolds's patent, No. 541,455, of June 18, A. D. 1895.

In the drawings, Figure 1 is a longitudinal section through a quadruple pump. I is the suction or inlet. O is the delivery or outlet. Fig. 2 is a transverse section on the line $\alpha-\alpha'$ of Fig. 1 as seen in the direction of the arrow α' . Fig. 3 is a transverse section on the line $y-y'$ of Fig. 1 as seen in the direction of the arrow y' .

Referring first to the case of multiple pumps, such as shown in Fig. 1, these are built up of end pieces and any desired number of intermediate sections, such as $a-a'$. Each of the sections has a partition, diaphragm, or wall b on the suction side, (herein referred to as the "front" side,) in which are openings or ports c , opening into passages d , formed between the front partition or diaphragm b and the rear partition or wall e . The chamber in which each section of the wheel g revolves is formed by the juxtaposition of two cavities or recesses $f-f'$, one of which is in the rear side of one of the sections, while the other is in the front side of the next section. In the case of the end chambers front and rear cavities $f-f'$ are formed in the end and rear walls of the end pieces, respectively.

In the passages d are return vanes or guides h , Fig. 3, so shaped as to prolong the sweep or curve of the immediately preceding guide-vanes k . The curved return-vanes h are tangential to the central opening in which the wheel g revolves and impart a rotary direc-

tion to the moving water, which is further increased by the front side of the partition e being given such a gradual return curve as to direct the water onto the curved part l of the boss of the wheel g . Part of the boss of one section of the wheel projects through the front partition or diaphragm b and directs the water into the section of the wheel in the next following chamber. The boss on the delivery side of one section of the wheel projecting through the front partition b forms a continuous curve with the part of the curved boss on the suction side of the next following wheel, thus forming a non-abrupt conduit for the water into the curved cavity of the wheel. 65

As shown in Fig. 1, the wheel is built up of a number of similar sections, such as g , (corresponding to the number of chambers,) each mounted on and keyed to a common shaft m . The blades n of the wheel are, as shown in the drawings, curved. They may be, however, radial or tangential in direction.

The passage for the water in each section of the wheel, as seen in longitudinal section slopes away in a curve from the curved boss 75 at the suction side, thus still further carrying into effect what is the essential feature of the present invention—namely, the avoiding of abrupt changes of direction or velocity of the water from one end to the other of the pump. 80

By the rotation of the wheel g the water is directed from its periphery between curved guide-vanes k , which are formed as projections on the rear side of the partition e and which form an easy path for the water to the 85 ports c , whence the water passes to the next passages d . By this combination of curved guides the water takes an easy spiral-like path of approximately uniform increase of curvature, and thus sudden changes in the direction of the flow of the water are avoided. The central openings in all the partitions b and e , as well as in the ends o and p , are coaxial and of equal radius. This feature greatly facilitates accuracy of manufacture, because when 95 two or more sections of the body of the pump are assembled together (without the wheels g and the shaft m) there is a straight clear way which enables all the openings to be bored so exactly to gage while in position as to insure 100

a very close running fit between the central openings and the bosses of the wheels. Leakage past the sections of the wheel is thereby reduced to a minimum and the efficiency of 5 the pump is improved.

As all the sections *g* of the wheel are mounted in the same direction on the shaft *m*—that is to say, the back of the first is toward the front of the second, and so on—there results a 10 pressure lengthwise of the shaft *m* toward the suction end of the pump. To balance this pressure, a disk or piston-like head *r* is attached to the shaft *m*. In Fig. 1 this disk or 15 piston-like head is shown as formed integral with the boss of the nearest wheel-section. It runs in a central chamber *s*, formed in the rear end piece *p*. It may, however, run in any of the central openings of the body of the pump.

20 The cavity *s* communicates, by means of the passage *t* and a connecting-pipe, with the suction end of the pump, so that by making the head *r* of suitable area the longitudinal pressure on the moving parts is wholly or partly 25 counterbalanced. No claim is, however, made herein to this longitudinal counterbalancing.

What we claim as our invention, and desire to secure by Letters Patent, is—

1. A rotary pump or turbine having a body 30 composed of end pieces and a plurality of hollow sections forming chambers for the reception of the wheel by the juxtaposition of cavities in alternate sections and in the end walls curved guides *k* forming spiral-like passages 35 external to the chambers, ports *e* intercommunicating therewith and with passages *d* formed by curved guides *h* in the next section, the said end pieces and sections having

central apertures for the reception of the wheel, the said central apertures being co- 40 axial and of equal radius, a wheel rotating therein and a water inlet and outlet substantially as and for the purpose set forth and shown.

2. A rotary pump or turbine consisting of 45 a wheel having a plurality of sections, each having a hollow interior with vanes therein and curved bosses on the suction and delivery sides, the hollow interior of one section, the curved boss on the suction side thereof, and the curved boss on the delivery side of the preceding adjacent section forming a path of 50 continuous curved contour, a pump-body having a plurality of chambers for containing the wheel, and curved guides, ports, and passages, the whole operating to direct the water in easy curved paths from the suction to the outlet side without abrupt changes of direction, substantially as set forth and shown. 55

3. In a multistage centrifugal turbine or 60 similar pump the combination of end pieces or heads and a plurality of intervening hollow sections having partitions or diaphragms for the reception of a multiple wheel or plurality of impellers mounted on a common shaft, the 65 central apertures of the heads or ends and those of the diaphragms or partitions being coaxial and of equal radius, substantially as set forth.

In witness whereof we have hereunto set our 70 hands in presence of two witnesses.

EDW. HOPKINSON.
ALAN E. L. CHORLTON.
